UNITED STATES PATENT OFFICE.

HAMILTON MORGAN, OF SAN FRANCISCO, CALIFORNIA.

EYE-CAP.

1,016,083.

Specification of Letters Patent.

Patented Jan. 30, 1912.

Application filed November 6, 1911. Serial No. 658,704.

To all whom it may concern:

Be it known that I, HAMILTON MORGAN, citizen of the United States, residing in the city and county of San Francisco and State 5 of California, have invented new and useful Improvements in Eye-Caps, of which the following is a specification.

My invention relates to eye-caps or devices for keeping the eyelids of the dead 10 closed.

The object of the present invention is to provide a simple, cheap, practical eye-cap, which will be transparent and therefore practically invisible when in position under 15 the lids thereby giving a neat and desirable appearance; and which cap is provided with an adhesive substance to prevent the eyelids from opening without resorting to the use of sharp projections or hooks which 20 are objectionable because they unnecessarily mutilate the bodies of the dead, and suggest the idea of harshness, which the modern undertaker desires particularly to avoid.

The invention consists of the parts and 25 the construction and combination of parts as hereinafter more fully described and claimed having reference to the accompanying drawings, in which the figure illustrates the invention.

30 A represents a spheroidal shell, which may be circular or oblong, preferably made of transparent celluloid and shaped to conform to the human eye. The outer surface of the shell or cap A is generally smooth, 35 but in order to maintain the eyelids closed, it has a portion of its surface applied with

an adhesive substance, such as animal glue, or dextrin. Preferably the cap is provided with a number of small perforations forming minute pockets for the glue or adhesive 40 and thereby insuring a more tenacious hold for the lids. When placed on the eyes of the dead the eyelids being once closed are prevented from opening again by means of the adhesive, and the natural appearance is 45 preserved, particularly by using a transparent cap, since the cap will not show through the tissues of the eyelid.

While I prefer to use celluloid, any other suitable material will do as isinglass, gelatin, silicate of soda or glass. Neither do I wish to limit myself to any particular adhesive; in fact I may make the entire eye-cap of silicate of soda or similar substance having adhesive properties when moistened. 50

Having thus described my invention what I claim and desire to secure by Letters Patent is—

1. An eye-cap having an adhesive exterior. 60

2. An eye-cap having perforations, an adhesive applied to the exterior of the eye-cap and filling the perforations.

3. An eye-cap of transparent material.

In testimony whereof I have hereunto set 65 my hand in the presence of two subscribing witnesses.

HAMILTON MORGAN.
